UNITED STATES PATENT OFFICE.

BEN B. DE MASTERS, OF KANSAS CITY, MISSOURI.

HAND-TOOL.

1,216,663.

Specification of Letters Patent. Patented Feb. 20, 1917.

Application filed November 20, 1913. Serial No. 802,076.

To all whom it may concern:

Be it known that I, BEN B. DE MASTERS, a citizen of the United States, residing at Kansas City, in the county of Jackson and 5 State of Missouri, have invented certain new and useful Improvements in Hand-Tools, of which the following is a specification.

This invention relates to improvements in tools for use principally in the grinding of 10 valves of internal combustion engines, and my special object is to devise a hand tool provided with a bit for engaging the valve and means for oscillating the bit, which means will permit of convenient oscillation 15 of the bit only through approximately a half revolution. It is also an object to produce a tool which may be conveniently operated to manipulate valves or other parts as to prohibit the use of other tools commonly employed for the purpose.

A further object is to provide a tool of few parts and hence of extremely simple construction and which will operate efficiently to perform the work required of it.

With these objects in view, the invention 25 consists in certain novel and peculiar features of construction and organization as hereinafter described and pointed out in the appended claims, and in order that it may 30 be fully understood reference is to be had to the accompanying drawing, in which—

Figure 1, is a side elevation of a tool embodying my improvements.

Fig. 2, is a longitudinal section of the 35 same.

Fig. 3, is a sectional detail of a modified form.

Referring to the drawing, the tool comprises a longitudinal member or post 2 on 40 the head of which is secured a disk 4, the latter being fixed to the post by means of a pin 6 extending through a hub formed on one side of the disk. On the end of the post at the opposite side of said disk is journaled a 45 sleeve 8, the end of the post being upset to retain said sleeve in place, and a pressure block 10 is carried by said sleeve, being bored to fit the same in tight relation.

Journalized on the post 2 is a yoke 12 forming a crank arm provided with a hand grip 14 journaled on its mid portion. The lower journaled portion of the yoke is provided with a series of clutch teeth 16, adapted to clutch a similar series of teeth 18 formed on 55 the sleeve 20 which is secured to the post 2

by a pin 22. In the preferred form as shown in Figs. 1 and 2, the post extends on through the sleeve and is provided with a terminal slot 24 in which to secure the shank of the bit 26 by means of a cotter 28.

60

In the grinding of the valves of explosive engines it is well known that continuous rotation of the valve is objectionable for the reason that the contacting surfaces of the valve and valve seat often become scored by the travel of an occasional large particle of grit or emery, entirely around the valve seat. This scoring forms pockets providing a still greater capacity for collecting carbon. It is therefore desirable that the valve be merely 65 oscillated instead of continuously rotated in order that such particles of grit may be ground and crushed before the position of the valve is materially changed.

70

While this desirability is recognized, the 75 workman in grinding the valves by means of the usual tools, such as a brace or breast bit, will frequently endeavor to speed the operation by continuously rotating the valve instead of exercising the care and patience 80 necessary to produce the better result by oscillating the tool as above described. With my improved form of tool it is obviously impracticable to use it for the purpose of imparting continuous rotation to the bit, because of the post 2 connecting the ends of the yoke 12 and standing in the way of the workman's arm after having moved the tool through approximately a half revolution. It is necessary therefore, for the workman to 85 perform his work by simply oscillating the tool, and as often as it is necessary to shift the position of the valve, he will lift the yoke or crank arm 12, and move the same to alter the relative engagement of the teeth 16 and 18. In making this change or shift the post and bit must remain stationary, and they may be so held by pressing down upon the member 10; however, for guarding 90 against any possibility of the post or bit moving at such times, the disk 4 is provided of such proportions as to be conveniently gripped by hand and held while the change is made.

95

The recess 24 is sufficiently large to permit slight rocking of the shank of the bit, so that the tool may be operated with the post tilted at a slight angle to the bit where the space about the valve is limited.

100

In the modification shown in Fig. 3, the 110

post 2 terminates within the sleeve 20, the latter being left with its lower end open to form a chuck for the stem 30 which carries the bit. This stem is provided with a tang 32 fitting in a recess 34 in the end of the post, and also with an annular groove 36 for receiving the end of a retaining screw 38 carried by the sleeve. A pin 22 secures the sleeve to the post, the same as in the form shown in Figs. 1 and 2.

It will of course be understood that the use of the device is not confined to the manipulation of valve grinding bits but that the same is well adapted for use in other relations where the only modification necessary is in the character of the tool proper applied to the end of the post 2. While I have illustrated what appear to me to be two desirable forms of the invention, I desire to reserve the right to all changes and modifications falling within the spirit and scope of the appended claim.

Copies of this patent may be obtained for five cents each, by addressing the "Commissioner of Patents, Washington, D. C."

I claim:—

In a hand tool for grinding valves, an unbroken cylindrical post, a disk secured thereon at one end and a bit secured to the other end, a pressure block journaled on one extremity of the post and bearing against the upper face of the disk, a sleeve provided with upwardly-projecting teeth, secured 25 rigidly on the post, and a yoke pivoted on and projecting radially from the post between the said sleeve and disk and provided with depending teeth for engagement with the teeth of the said sleeve; said yoke being 30 adapted for slidable movement upward on the post to withdraw the yoke teeth from engagement with the teeth of the sleeve.

In testimony whereof, I affix my signature, in the presence of two witnesses.

BEN B. DE MASTERS.
